CHUCKING AND DRIVING DEVICE

William J. Nightingale, Oak Park, Ill., assignor of
one-half to George C. Bruen

Application October 25, 1944, Serial No. 560,261

19 Claims. (Cl. 82—40)

This invention relates to a chucking and driving device, and more particularly to a device adapted for attachment to the live spindle of a lathe.

The devices disclosed and claimed here comprise improvements of devices of the kind shown and claimed in my copending application Serial No. 495,141, filed July 17, 1943, entitled "Universal multi-dogging device, now Patent No. 2,367,045, granted January 9, 1945.

One of the features of this invention is that it provides an improved driving or dogging device for use on a lathe; another feature of this invention is that a single unit of the character disclosed here may be used throughout a range of work piece sizes that heretofore has required the use of a multiplicity of dogs of the prior conventional type; still another feature of this invention is that the work piece may be very quickly and accurately clamped in position in proper relation to the center point element of the driving spindle of a lathe; yet another feature of this invention is that the device is so constructed and arranged as to compensate for any slight misalignment between the axis of the work piece and the axis of the center point element; a further feature of this invention is the provision of spring means biasing the movable mounting member of the device to a desired normal position in perfect alignment with the axis of the center point element; yet a further feature of this invention is that the work may be held tightly against the center point element without the use of a bridle or strap; and still a further feature of this invention is that the device is operated as a two jaw chuck when desired. Other features and advantages of this invention will be apparent from the following specification and the drawings, in which:

Figure 1 is a front elevational view of a preferred form of device embodying my invention; Figure 2 is a side elevational view of the device shown in Figure 1 with part of the cylindrical guard housing broken away; Figure 3 is a vertical sectional view along the line 3—3 of Figure 2; Figure 4 is a vertical sectional view at right angles to that of Figure 3, along the line 4—4 of Figure 1;

Figure 5 is a top plan view of the device with the housing partly broken away; Figure 6 is a partial vertical sectional view along the line 6—6 of Figure 4; Figure 7 is a fragmentary horizontal sectional view along the line 7—7 of Figure 6; Figure 8 is a fragmentary detail sectional view along the line 8—8 of Figure 3; Figure 9 is a front elevational view of another form of device em-

bodying my invention; Figure 10 is a vertical sectional view of this device along the line 10—10 of Figure 9; Figure 11 is a top plan view of the device shown in Figure 9 with part of the housing broken away; Figure 12 is a partial vertical sectional view along the line 12—12 of Figure 10; Figure 13 is a horizontal sectional view along the line 13—13 of Figure 10; Figure 14 is a fragmentary detail sectional view along the line 14—14 of Figure 10; Figure 15 is a detail plan view of another form of connection for one end of the mounting member of the device shown in Figure 9; and Figure 16 is a fragmentary sectional view along the line 16—16 of Figure 15.

15 The majority of work on a lathe is done with the work piece supported between the live or head stock and the tail stock. There are many situations, however, where the work cannot be done with the tail stock in place. Under these circumstances some holding and driving connection must be made between the work piece and the driving spindle, the other end of the work piece usually being supported in a steady rest. The above-mentioned connection has heretofore been 20 commonly provided by the use of a dog, the dog having an open body portion within which the work piece is received and clamped, and an L-shaped tail adapted to be received in a radial slot in a face plate which must be attached to the 25 driving spindle. In some cases a straight tailed dog is used in connection with a face plate having a driving stud. In either case, it is necessary to have a plurality of dogs and to use different dogs of the set for work pieces of different size, each 30 dog being capable of use through only a very small range of work piece size. Further, this arrangement has an off-center or unbalanced effect which is hard on the lathe and which sometimes results in vibration of the work piece. Furthermore, 35 particularly where the dog has an L-shaped tail, there is a bending torque, exerted through a leverage effect on the work piece, which sometimes results in appreciable bending or bowing of the work piece particularly in smaller size rods or tubes an inch and a half or less in diameter. 40 The use of a dog also requires some kind of holding means to keep the work piece pulled up tight against the center point element, a bridle or strap generally being used. This is awkward, frequently 45 loosens up, and sometimes breaks.

Chuck and driving devices embodying my invention are capable of handling a very wide range of sizes of work piece, can be left practically permanently on the driving spindle, and ensure 50 perfect holding and clamping of the work piece

without any undesired bending or other strains on the work piece. Furthermore, while the device includes means permitting desired movements of various kinds between certain parts, the driving connection is at all times positive and direct, without any play enabling vibration of the work piece during its driving rotation.

Referring now more particularly to the specific embodiment of my invention illustrated in Figures 1-8, the device is shown in position on the head of a lathe having a live or driving spindle 10 including a threaded hub portion 10a and a center point element 10b. Threaded on to the hub 10a is one portion 11a of a supporting member identified in general at 11, the connection being screwed up tight to provide a rigid mounting rotatable with the driving spindle. The other portion 11b of the supporting member is mounted on the portion 11a for rotational and axial movement with respect thereto, what is here being termed axial being movement parallel to the axis of the spindle or center point element rotation. Referring now more particularly to Figures 4, 6 and 7, it will be seen that pins 12a and 12b are fixedly mounted in opposite sides of the supporting member portion 11a and are received within angularly disposed slots 11b' and 11b'' in the outer supporting member 11b. Because of the angular disposition of the slots, as is best seen in Figure 7, rotation of the portion 11b with respect to the portion 11a effects axial movement of the portion 11b. As will be more fully apparent later, this axial movement is of considerable advantage in pulling a work piece up against the center point element 10b and keeping it snugly thereagainst during operation of the lathe.

The outer supporting member portion 11b carries rigidly mounted thereon one element, here the socket element, of a universal or ball and socket joint. The socket element is here shown as comprising two annular pieces 13 and 14 having their inner surfaces ground or otherwise shaped to provide a concave band which is an annular portion of a spherical surface. The other or ball element of the joint, here identified as 15, has a convex partial spherical surface adapted to be received within and cooperate with the concave surface, the parts 13, 14 and 15 comprising a joint capable of at least limited universal movement, the ball part 15 carrying a mounting member and clamping jaws to be hereafter described. The joint portion of the device has been described, merely as a matter of convenience, as though it were an independent and distinct portion of the device; but it would be understood that, for all operative purposes, the socket element of the joint is part of the supporting member and the ball part of the joint is part of the mounting clamping means carried by the supporting member. As may be best seen in Figure 1, the annular part 13 is provided with a plurality of outwardly extending radial arms here identified as 13a-d, the outer ends of these arms serving as the supporting means for a cylindrical housing or guard member 16 enclosing the mounting and clamping parts of the device.

Inasmuch as driving or rotating force delivered from the spindle to the outer or socket portion of the joint must be transmitted to the inner or ball portion 15 of the joint, drive connection means is provided which prevents circumferential movement between these parts but permits any other desired movement therebetween, at least through the limited range necessary for proper operation of this device. Referring more particularly to

Figures 6 and 8, it will be seen that a drive pin 17 is journalled in the outer socket portion of the joint comprising the parts 13 and 14, and has its head rigidly connected to a slide block 18 slidable in a slot 15' in the ball element. This slot extends axially, and since the block 18 is a tight, although sliding, fit therein, circumferential movement between the joint parts is prevented and there is a positive driving connection between these parts with no play or lost motion. The term circumferential movement is here being used in connection with rotative movement about a center concentric with the axis of rotation of the spindle and center point element of the lathe. This driving connection between the parts is such, however, that the ball part may twist in its socket in any combination of movements about two axes perpendicular to each other and to the axis of rotation of the spindle, one of these axes of movement of the joint parts coinciding with the axis of the drive pin 17. The result of this construction is that the ball part may move sufficiently to compensate for any slight angular misalignment between the axis of the work piece and the axis of rotation of the spindle, and this compensating movement may take place constantly during driving operation without in any way impairing the positive driving connection.

The ball element 15 carries a mounting member here identified in general as 20. As may be best seen in Figure 1, this mounting member 20 has a main transverse body portion operating as a slide and serving as means for carrying the clamping jaws 21 and 22, these latter being slidably movable toward and away from each other in a radial direction, speaking with respect to the axis of rotation of the spindle. Plate members or backing means 21a and 22a are fixedly mounted in the member 20 and have studs 21b and 22b rotatably mounted therein in such a manner as to be prevented from axial movement. The thread portions of the studs are threaded into cooperating openings in the clamping members 21 and 22, so that the studs comprise means for moving the body members into clamping engagement with a work piece 23. Openings 16a and 16b in the guard housing provide access to the studs 21b and 22b.

As may be best seen in Figure 4, the mounting member 20 is connected to the ball element 15 in such a manner that it is slidably movable with respect thereto. This connection is effected by a bolt 24 snugly received within a vertical slot in the member 15, so that any movement of the member 20 with respect to the ball element 15 is vertical as viewed in Fig. 4, the bolt moving in the slot, or due to the over-sized opening 15a such movement may be a swinging movement about bolt 24 as a center. In order to complete the connection another bolt 25 is provided, this bolt being snugly received in an appropriate opening in the mounting member 20, but being received in an over-size opening 15a in the ball element, so that movement between the parts is permitted. This construction prevents circumferential movement between the mounting member 20 and the ball element 15, but permits other movement in a plane transverse to the axis of the spindle. As will be readily apparent, this construction, by virtue of the ball and socket joint, automatically compensates for any angular misalignment between the axis of the work piece 23 and that of the spindle 10; and the movement of the mounting member 20 with respect to the ball part 15, in a plane transverse to the axis of the spindle, automatically compensates for any lateral misalign-

ment of the work piece and spindle, or for unequal tightening of the jaws 21 and 22. The result is that the two clamping jaws shown can be drawn up on the bar or tube comprising the work piece, the work piece properly and accurately positioned with respect to the center point element 10b, and any slight misalignment present, particularly when a steady rest is being used, being automatically compensated for without strain on the work piece by the movements permitted in the driving device during its driving operation. The angle of the slots 11b' and 11b'' are such that driving rotation of the spindle, working against the resistance of the work piece to rotation, tends to cause the outer mounting member portion 11b to move back toward the lathe head, this action automatically keeping the work piece snugly against the center point element 10b. When the lathe is stopped and it is desired to move the work piece either toward or away from the center point element 10b, however, this is very easily accomplished manually by merely grasping the cylindrical housing member 16 and rotating it a little in one direction or the other while keeping the spindle stationary.

In order to initially maintain the mounting member and clamping parts in a normal desired position during setup and the like, I provide spring means biasing these parts to desired position exactly transverse to and centered with respect to the axis of rotation of the spindle 10. As may be best seen in Figures 1 and 5, the mounting member 20 is provided with sidewardly extending (speaking with respect to the position of the parts as shown in Figure 1) arm portions 20a and 20b, these terminating in ball parts 20a' and 20b'. Cooperating with each of these ball parts is a pair of spring assemblies here identified in general as 27 and 28. While these spring assemblies may for convenience be stamped out of only one or two pieces of spring metal, they are for all operative purposes composed of three leaf springs, which may be identified as 27a—c on the one hand and 28a—c on the other hand. The pair of opposed spring pieces 27a and 27c on the one hand, and 28a and 28c on the other hand, cooperate with ball parts normally to urge the mounting member and the parts carried thereby to the desired normal position, being assisted in this by the opposing action of the springs 27b and 28b tending to center these parts laterally. This spring means or spring arrangement for biasing the parts to a desired normal position is highly important in practice, since it assists in accurately centering and properly clamping the work piece without undue time or difficulty in the setup operation. For some purposes, particularly where the device is to be used as a two jaw chuck, I find it desirable to be able to lock the mounting member and parts carried thereby in rigid relation to the supporting member. To accomplish this I provide the mounting member (or, speaking more precisely, the joint part 14) with bosses 14a and 14b. In registry with these bosses I provide lugs 20c and 20d through which I pass studs 29 and 30 with pointed ends adapted to be received in conical depressions in the bosses 14a and 14b when the studs are screwed in, as shown in the drawings. This makes the whole assembly rigid and provides a very efficient two jaw chuck. It will be understood, of course, that these studs are backed out to permit the desired freedom of movement between the parts when the device is merely acting as a driving device and the other end of the work

piece is engaged by the tail stock or by a steady rest.

Referring now more particularly to the embodiment of my invention illustrated in Figures 9-14, it will be seen that this form of my invention has some features similar to those of the dogging devices shown in my above-mentioned copending application Serial No. 495,141, although in many respects this device corresponds to the device earlier described. In so far as possible, therefore, parts of this form which correspond with parts of the device shown in Figures 1-8 will be marked with analogous reference numerals differing by thirty from those used in the earlier figures, so that the description can be shortened.

In this form of the device the threaded hub 40a of the spindle carries a supporting member 41 which in turn carries a mounting member 50 on which are movably mounted clamping jaws 51 and 52. The supporting member also carries a cylindrical housing member 46. In this form of my invention the supporting member is a single piece, the desired axial movement of the mounting and clamping members being effected by the use of pins 61 and 62 axially movable in appropriate openings in the supporting member 41. The ends of the pins 61 and 62 are engaged by a cam ring 63 rotatably mounted on a supporting member 41. As may be best seen in Figure 13, the cam ring has a pair of depressed portions, as the portion 63a, which enable the pins to lie in the position shown in the drawings when these depressed portions register with the pins. When the cam ring is rotated by a hand rod, however, the pins may be pushed to the right (speaking with respect to the position of the parts as illustrated in Figure 10) to force the mounting and clamping members to the right. This movement is permitted by virtue of the fact that the mounting member is connected to the supporting member by mounting pin members here identified as 64 and 65, the cylindrical shank portions of these members being axially slideable in the openings in the supporting member 41 receiving them. The mounting pin members and mounting and clamping members are normally urged axially in a direction toward the head stock by springs 66 and 67 operative on the pins and the supporting member. When the cam ring 63 is in the position shown in the drawings the mounting and clamping members are urged toward the spindle by the springs 66 and 67, thus holding the work piece against the center point element, not shown in these drawings. When it is desired to insert a work piece, the cam ring would first be rotated to forceably move the mounting pin members, mounting member and clamping members to the right, and then the jaws or clamping members of the device would be pulled into engagement with the work piece. In setting up after the work piece is properly clamped in the device, the cam ring would be turned to the position shown in the drawings and the springs 66 and 67 would then keep the work piece against the center point element. In this respect the device shown here is similar to that more fully described and claimed in my above-mentioned copending application Serial No. 495,141.

The transverse mounting member is again provided with sidewardly extending arm portions analogous to those shown in the device first described here, these being identified as 50a and 50b and terminating in ball parts 50a' and 50b'. These ball parts again cooperate with two spring

assemblies rigidly mounted on the supporting member, these spring assemblies being here shown as comprising the three leaf spring parts 51a-c on the one hand and 58a-c on the other hand. This arrangement again provides means biasing the mounting and clamping parts to a desired normal center position with respect to the spindle, although they have sufficient yield to permit desired movement during operation without stress on the work piece. When it is desired to lock the device rigidly, studs 59 and 60 in lugs 50c and 50d may be screwed in to bear against bosses on the supporting member 41.

The mounting of the mounting member 50 in the mounting pin members 64 and 65 is in general analogous to the mounting arrangement shown in my aforementioned copending application Serial No. 495,141, and it will therefore not be described in undue detail. The top and bottom portions of the mounting member 50 (speaking with respect to the position of the parts as shown in Figure 10) are formed into trunnion portions here identified as 50e and 50f. As may be best seen in Figures 10 and 11, the upper trunnion portion is journaled in a mounting block 70 which is spring supported for limited movement in any direction in the mounting pin member 64. As may be best seen in Figure 14, the lower trunnion end portion 50f is journaled in a mounting block 71 which is axially slidable in the frame portion of the mounting pin member 65. It will be apparent that there can be no circumferential movement between the lower end of the mounting member and the supporting member, so that when the work piece is drawn up tight against the center point element there is a positive drive arrangement with no circumferential play. On the other hand, in setting up the work piece, the full freedom of movement (through a limited range) provided the upper end of the mounting member enables proper centering of the work piece on the center point element of the spindle. In and out movement of both of the ends of the mounting member, combined with the fact that the member can rotate about an axis through its trunnion end portions, enables it to compensate for angular misalignment between the axis of the work piece and the axis of rotation of the spindle; and the lateral movement permitted by the mounting of the upper end and mounting block 70, coupled with the fact that the mounting member can move vertically by sliding of the trunnions in their mounting blocks 70 and 71, enables compensation for any lateral or vertical displacement of the axis.

Referring now more particularly to Figures 15 and 16, I show an improved mounting arrangement for the end of the mounting member which is to have limited movement in several directions in the mounting pin member supporting it. In this case the trunnion end portion 80e of the mounting member is slidably and rotatably journaled in a bearing member 81 held within an annular sleeve 82 of resilient material, as rubber, this sleeve in turn being mounted in the mounting pin member 94. This provides a very simple and tight arrangement which nevertheless permits the desired axial or lateral movement of this end of the trunnion with respect to the mounting pin member carrying it. This has very considerable advantages, both in initial assembly and in freedom from breakage or other trouble, and comprises an improvement over the arrange-

ment shown in the device illustrated more fully in Figures 9-14.

While I have shown and described certain embodiments of my invention, it is to be understood that it is capable of many modifications. Changes, therefore, in the construction and arrangement may be made without departing from the spirit and scope of the invention as disclosed in the appended claims.

10 I claim:

15 1. A driving device adapted to be attached to a rotating member having a center point element and to clamp a piece of work in proper relation to said element, including: a supporting member adapted to be rigidly attached to said rotating member; a mounting member mounted on said supporting member in such manner that circumferential movement is prevented but other movement with respect to the supporting member is permitted through at least a limited range; 20 spring means biasing the mounting member to a desired normal position relative to the supporting member; clamping members movably mounted on the mounting member; and means for moving said last mentioned members toward each other to clamp the piece of work therebetween.

25 2. A driving device adapted to be attached to a rotating member having a center point element and to clamp a piece of work in proper relation to said element, including: a supporting member adapted to be rigidly attached to said rotating member; a mounting member mounted on said supporting member in such manner that circumferential movement is prevented but other movement with respect to the supporting member is permitted both in a plane transverse to the axis of the center point element and about an axis perpendicular to and intersecting the axis of the center point element; spring means biasing the mounting member to a desired normal position relative to the supporting member; clamping members movably mounted on the mounting member; and means for moving said last mentioned members toward each other to clamp the piece of work therebetween.

30 3. A driving device adapted to be attached to a rotating member having a center point element and to clamp a piece of work in proper relation to said element, including: a supporting member adapted to be rigidly attached to said rotating member; a mounting member mounted on said supporting member in such manner that circumferential movement is prevented but other movement with respect to the supporting member is permitted both in a plane transverse to the axis of the center point element and about an axis perpendicular to and intersecting the axis of the center point element; spring means comprising at least two spring elements at each of at least two points on opposite sides of the axis of the center point element biasing the mounting member to a desired normal position relative to the supporting member; clamping members movably mounted on the mounting member; and means for moving said last mentioned members toward each other to clamp the piece of work therebetween.

35 4. A driving device adapted to be attached to a rotating member having a center point element and to clamp a piece of work in proper relation to said element, including: a supporting member adapted to be rigidly attached to said rotating member; a mounting member mounted on said supporting member, a driving connection element mounted between the mounting member

and supporting member in such manner that relative circumferential movement is prevented but the driving connection element may twist about two axes perpendicular to each other and to the axis of rotation of said rotating member; means connecting the mounting member to the driving connection element for lateral movement therebetween; clamping members movably mounted on the mounting member; and means for moving said last mentioned members toward each other to clamp the piece of work therebetween.

5. A driving device adapted to be attached to a rotating member having a center point element and to clamp a piece of work in proper relation to said element, including: a supporting member adapted to be rigidly attached to said rotating member; a mounting member, one of said members having a ball portion and the other having a cooperating socket portion; means providing a driving connection between the mounting member and supporting member in such manner that circumferential movement is prevented but the ball portion may twist about two axes perpendicular to each other and to the axis of rotation of said rotating member; means connecting the mounting member to the ball portion for lateral movement therebetween; clamping members movably mounted on the mounting member; and means for moving said last mentioned members toward each other to clamp the piece of work therebetween.

6. A driving device adapted to be attached to a rotating member having a center point element and to clamp a piece of work in proper relation to said element, including: a supporting member adapted to be rigidly attached to said rotating member; a mounting member, one of said members having a ball portion and the other having a cooperating socket portion such that the mounting member is mounted on said supporting member for universal movement with respect thereto, the remainder of the mounting member being slidably movable with respect to its portion of the ball and socket arrangement; means providing a driving connection between the mounting member and supporting member in such manner that circumferential movement is prevented but other movement with respect to the supporting member is permitted through at least a limited range; means connecting the mounting member to the ball portion for lateral movement therebetween; clamping members movably mounted on the mounting member; and means for moving said last mentioned members toward each other to clamp the piece of work therebetween.

7. A driving device adapted to be attached to a rotating member having a center point element and to clamp a piece of work in proper relation to said element, including: a supporting member adapted to be rigidly attached to said rotating member; a mounting member; a universal joint comprising ball and socket parts, one of said parts being rigidly connected to one of said members and the other of said parts being connected to the other member in such manner that circumferential movement is prevented but sliding movement in a plane transverse to the axis of the center point element is permitted; means providing a driving connection between the parts of the joint in such manner that circumferential movement is prevented but other movement between the parts is permitted; clamping mem-

bers movably mounted on the mounting member; and means for moving said last mentioned members toward each other to clamp the piece of work therebetween.

5 8. A driving device adapted to be attached to a rotating member having a center point element and to clamp a piece of work in proper relation to said element, including: a supporting member adapted to be rigidly attached to said rotating member; a mounting member; a universal joint comprising ball and socket parts, one of said parts being rigidly connected to one of said members and the other of said parts being connected to the other member in such manner as to permit sliding movement in a plane transverse to the axis of the center point element, this latter connection including means preventing relative circumferential movement; means providing a driving connection between the parts of the joint in such manner that relative circumferential movement is prevented but other movement between the parts is permitted; clamping members movably mounted on the mounting member; and means for moving said last mentioned members toward each other to clamp the piece of the work therebetween.

9. A driving device adapted to be attached to a rotating member having a center point element and to clamp a piece of work in proper relation to said element, including: a supporting member comprising two portions movable with respect to each other along the axis of the center point element, one of said portions being adapted to be rigidly attached to the rotating member; a mounting member mounted on the other portion of the supporting member in such manner that circumferential movement is prevented but other movement with respect to the supporting member is permitted through at least a limited range; spring means biasing the mounting member to a desired normal position relative to the supporting member; clamping members movably mounted on the mounting member; and means for moving said last mentioned members toward each other to clamp the piece of work therebetween.

10. A driving device adapted to be attached to a rotating member having a center point element and to clamp a piece of work in proper relation to said element, including: a supporting member comprising two portions movable with respect to each other along the axis of the center point element, one of said portions being adapted to be rigidly attached to the rotating member; a mounting member mounted on the other portion of the supporting member for universal movement with respect thereto; means providing a driving connection between the mounting member and supporting member in such manner that circumferential movement is prevented but other movement with respect to the supporting member is permitted through at least a limited range; clamping members movably mounted on the mounting member; and means for moving said last mentioned members toward each other to clamp the piece of work therebetween.

11. A driving device adapted to be attached to a rotating member having a center point element and to clamp a piece of work in proper relation to said element, including: a supporting member comprising two portions movable with respect to each other along the axis of the center point element, one of said portions being

adapted to be rigidly attached to the rotating member; a mounting member; a universal joint comprising ball and socket parts, one of said parts being rigidly connected to one of said members and the other of said parts being connected to the other member in such manner as to permit sliding movement in a plane transverse to the axis of the center point element, this latter connection including means preventing circumferential movement; means providing a driving connection between the parts of the joint in such manner that circumferential movement is prevented but other movement between the parts is permitted; clamping members movably mounted on the mounting member; and means for moving said last mentioned members toward each other to clamp the piece of the work therebetween.

12. Apparatus of the character claimed in claim 7, including screw means for locking the mounting member in a desired normal position relative to the supporting member.

13. A driving device adapted to be attached to a rotating member having a center point element and to clamp a piece of work in proper relation to said element, including: a supporting member comprising two portions rotatable with respect to each other to effect movement therebetween along the axis of the center point element, one of said portions being adapted to be rigidly attached to the rotating member; a mounting member mounted on the other portion of the supporting member in such manner that circumferential movement is prevented but other movement with respect to the supporting member is permitted through at least a limited range; clamping members movably mounted on the mounting member; and means for moving said last mentioned members toward each other to clamp the piece of work therebetween.

14. A driving device adapted to be attached to a rotating member having a center point element and to clamp a piece of work in proper relation to said element, including: a supporting member comprising two portions rotatable with respect to each other to effect movement therebetween along the axis of the center point element, one of said portions being adapted to be rigidly attached to the rotating member; a cylindrical housing member rigidly attached to the other portion; a mounting member mounted on the other portion of the supporting member in such manner that circumferential movement is prevented but other movement with respect to the supporting member is permitted through at least a limited range; clamping members movably mounted on the mounting member; and means for moving said last mentioned members toward each other to clamp the piece of work therebetween.

15. A driving device adapted to be attached to a rotating member having a center point element and to clamp a piece of work in proper relation to said element, including: a supporting member adapted to be rigidly attached to said rotating member; a transverse mounting member mounted on said supporting member in such manner that circumferential movement is prevented but other movement with respect to the supporting member is permitted through at least a limited range, said transverse member having arm portions extending from the sides thereof; spring means on the supporting member and cooperating with said arm portions for biasing the

mounting member to a desired normal position relative to the supporting member; clamping members movably mounted on the mounting member; and means for moving said last mentioned members toward each other to clamp the piece of work therebetween.

16. A driving device adapted to be attached to a rotating member having a center point element and to clamp a piece of work in proper relation to said element, including: a supporting member adapted to be rigidly attached to said rotating member; a transverse mounting member mounted on said supporting member in such manner that circumferential movement is prevented but other movement with respect to the supporting member is permitted through at least a limited range, said transverse member having arm portions extending from the sides thereof and terminating in ball parts; spring means comprising three leaf spring elements cooperating with each of said ball parts for biasing the mounting member to a desired normal position relative to the supporting member; clamping members movably mounted on the mounting member; and means for moving said last mentioned members toward each other to clamp the piece of work therebetween.

17. A driving device adapted to be attached to a rotating member having a center point element and to clamp a piece of work in proper relation to said element, including: a supporting member adapted to be rigidly attached to said rotating member; a transverse mounting member mounted on said supporting member in such manner that circumferential movement is prevented but other movement with respect to the supporting member is permitted through at least a limited range, the connection between one end of the transverse member and the supporting member including a block of resilient material; clamping members movably mounted on the mounting member; and means for moving said last mentioned members toward each other to clamp the piece of work therebetween.

18. A driving device adapted to be attached to a rotating member having a center point element and to clamp a piece of work in proper relation to said element, including: a supporting member adapted to be rigidly attached to said rotating member; a transverse mounting member mounted on said supporting member in such manner that circumferential movement is prevented but other movement with respect to the supporting member is permitted through at least a limited range, the connection between one end of the transverse member and the supporting member including a block of resilient material, the connection between the other end of the transverse member and the supporting member being so constructed as to permit axial movement of such end but prevent circumferential movement thereof; clamping members movably mounted on the mounting member; and means for moving said last mentioned members toward each other to clamp the piece of work therebetween.

19. A driving device adapted to be attached to a rotating member having a center point element and to clamp a piece of work in proper relation to said element, including: a supporting member adapted to be rigidly attached to said rotating member; a mounting member; a universal joint comprising ball and socket parts, one of said parts being rigidly connected to one of said members and the other of said parts being connected to

the other member in such manner that circumferential movement is prevented but sliding movement in a plane transverse to the axis of the center point element is permitted; means providing a driving connection between the parts of the joint in such manner that circumferential movement is prevented but other movement between the parts is permitted; clamping members

movably mounted on the mounting member; means for moving said last mentioned members toward each other to clamp the piece of work therebetween; and spring means biasing the mounting member to a desired normal position relative to the supporting member.

WILLIAM J. NIGHTINGALE.
